PRY TYPE JAR CAP REMOVER

Filed Oct. 18, 1946

UNITED STATES PATENT OFFICE

2,571,401

PRY TYPE JAR CAP REMOVER

Raymond H. Williams, Chicago, Ill., assignor to
 White Cap Company, Chicago, Ill., a corpora-
 tion of Delaware

Application October 18, 1946, Serial No. 704,253

5 Claims. (Cl. 81—3.46)

1

My invention is concerned with improvements in an opener or tool for use in removing the closure cap or lid from a receptacle.

Closure caps or lids of the pry-off type (as distinguished from the screw-off type) have long been used on receptacles such as glass bottles and jars for putting up various kinds of products, particularly foods. The most popular pry-off cap now in use is the type such as shown in Patent No. 2,339,827, issued January 25, 1944, to William P. White.

Practically all containers on which the pry-off type of cap is employed have an annular abutment shoulder which is located a short distance below the skirt of the cap, when the latter is in fully closed position on the container, which shoulder serves as a fulcrum for use in prying off the cap. The housewife generally resorts to the blade of a knife or the bowl or handle of a spoon to pry off the cap. Such a pry-off means has proven very unsatisfactory because the caps are difficult to get off and likely to mar the knife or spoon used.

It is an object of my invention to provide an opener tool which is easy to use and which is especially effective for removing pry-off caps of the type referred to or of similar type.

It is a further object of my invention to provide a simple and effective tool for use in removing pry-off type container closures which comprises a blade-like projecting member adapted for insertion between the skirt of the closure and an abutment shoulder provided on the container and handle means for rotating the blade-like member to force the closure from the container without damage to the container or the closure.

These and other objects will be apparent from a description of the preferred form of my opener tool which is shown by way of illustration in the accompanying drawings, wherein:

Fig. 1 is a view, partially in section, showing the top of a jar having a pry-off cap secured thereon, and an opener tool embodying the principles of my invention, the tool being shown with the end of the opener blade between the pry-off ledge of the jar and the skirt of the cap and with the opener blade partially rotated into operative position preparatory to prying off the cap;

Fig. 2 is an elevation of the opener;

Fig. 3 is an end view of the opener blade;

Fig. 4 is a section on the line 4—4 of Fig. 2;

Fig. 5 is a section on the line 5—5 of Fig. 2;

2

Fig. 6 is an elevation of a modification of the opener; and

Fig. 7 is an elevation of a further modification of the opener.

The preferred form of my opener and the manner in which it is used to remove a pry-off type closure cap from a glass jar are illustrated in Figs. 1 to 5 of the drawings. Referring to Fig. 1 the jar 10 is provided with a mouth portion 11 over which the cap 12 is positioned and with an annular pry-off shoulder or ledge 13 which is located a short distance below the skirt 14 of the cap 12, when the cap 12 is in fully closed position. The annular shoulder 13 serves as a fulcrum for use in prying off the cap 12.

My opener is characterized by a relatively wide flat blade-like member 16 and a handle member 17. The blade member 16 is generally rectangular in cross section as shown in Figs. 3 to 15 inclusive, having relatively wide flat side faces 18 and 19 and relatively narrow side edges 20 and 21. The end edge 22 is curved on a concave arc. Closely adjacent the end edge 22 the blade member 16 is relieved or grooved at 23 and

24. The grooves 23 and 24 extend from the edges 20 and 21 toward the center of the side faces 18 and 19 and are rounded or curved transversely on a concave arc. The handle member 17 is sufficiently large to be comfortably gripped in one hand. It is joined to the blade member 16 at a sufficient distance from the operating end of the same to provide adequate clearance for the fingers of the user.

In using my opener the end of the blade member 16 is inserted flatwise between the pry-off shoulder 13 of the jar 10 and the skirt 14 of the cap 12. The concave end edge 22 of the blade member 16 aids in properly locating the blade member 16 between the pry-off shoulder 13 and the cap skirt 14. The handle member 17 is then rotated in either direction until the lower edge of the skirt 14 is engaged in interlocking relation with one of the grooves 23 and 24. The engagement of the skirt 14 in the selected groove 45 prevents the tool from slipping out of engagement with the cap 12 during the opening operation. Upon further rotation of the handle 17 the blade 16 forces the cap 12 upwardly until it is free of the jar mouth. All the engaging surfaces are rounded and there is no damage to the cap 12 so that it may be replaced on the jar mouth 11 for resealing the jar, if desired.

In Fig. 6 I have illustrated a modified form of opener 30 having an operating blade 31 and a handle member 32. The operating blade 31 is

identical with the blade 16 illustrated in Figs. 1 to 5 inclusive. The handle member 32 extends at an angle to the longitudinal axis of the blade 32 and is of sufficient size and configuration to provide a comfortable grip. The opener 30 is used in the same manner as opener 15.

In Fig. 7 I have illustrated a further modified form of opener 40. In this form the blade 41 is identical with that shown in Figs. 1 to 5 inclusive. The handle member 42 extends along the longitudinal axis of the blade 41 and is of sufficient size to provide a comfortable grip. The opener 40 is operated in the same manner as opener 15, the blade 41 being rotated or turned by rotating or twisting the handle 42.

In all the forms illustrated the opener members may be made of any desired material or combination of materials. Preferably, the opener is stamped of metal to provide a flat one-piece device which may be economically manufactured.

While I have illustrated specific details of construction, it will be understood that other details of construction may be resorted to within the spirit of my invention.

I claim:

1. A tool for use in removing caps of the pry-off type from a receptacle having an annular abutment shoulder located below the skirt of the pry-off cap, said tool comprising a blade having a relatively wide flat end portion terminating in a concave end edge, said end portion being provided with tapered concave grooves spaced from said end edge a distance substantially equal to the distance of the lower edge of the skirt of the cap from the receptacle and extending from the side edges of said blade toward the center on each side face thereof, and a handle member on said blade whereby when said end portion of said blade is inserted between the skirt of the pry-off cap and the annular abutment shoulder of the receptacle and said handle is rotated to twist said blade one of said grooves will index with the skirt of said cap and said cap will be forced from said receptacle.

2. A tool for use in removing caps of the pry-off type from a receptacle having an annular abutment shoulder located below the skirt of the cap, said tool comprising a forwardly extending portion characterized by spaced generally parallel side edges and a front edge connecting said side edges in generally right-angular relation to the latter, said forwardly extending portion being provided adjacent its front end in its upper and lower faces with laterally extending grooves, which grooves intersect said side edges and are spaced rearwardly from said front edge a distance substantially equal to the distance of the lower edge of the skirt of the cap from the receptacle, and a handle characterized by wing portions which extend laterally in opposite directions from the base of said forwardly extending portion, whereby when said front edge of said forwardly extending portion is inserted between the skirt of the cap and the annular abutment shoulder of the receptacle and said handle is rotated to twist said forwardly extending portion one of said grooves will index with the skirt of the cap and the cap will be forced upwardly from the receptacle.

3. An opener for caps of the pry-off type mounted on jars having ledges spaced beneath the caps, comprising a relatively wide, thin, flat forwardly extending member adapted for insertion in the annular space between the rim of the

cap and the ledge on the jar, and a handle for imparting a twisting movement to said forwardly extending member, said forwardly extending member having a front edge which is curved to conform generally to the periphery of the jar between the rim of the cap and the ledge, and said forwardly extending member having side edges which extend rearwardly from the ends of the front edge and which are adapted to bear respectively against the under surface of the rim and the upper surface of the ledge at points spaced circumferentially of the jar, said forwardly extending member being provided with recesses in the flat faces thereof at points spaced rearwardly from said front edge a distance substantially equal to the distance of the lower edge of the rim of the cap from the jar and extending inwardly of the side edges thereof, one of said recesses being adapted to engage in interlocking relation with the rim irrespective of the direction in which the blade is twisted by the handle.

4. A tool for removing caps of the pry-off type from a container having an annular abutment shoulder located below the skirt of the cap, said tool comprising a blade-like portion having a front edge and laterally spaced side edges extending rearwardly from the ends of the front edge, said blade-like portion being provided at its side edges with inwardly extending groove formations which are spaced from the front edge a distance substantially equal to the distance of the lower edge of the skirt of the cap from the container and a handle extending laterally of the rear of said blade-like portion whereby when said blade-like portion is inserted between the skirt of the cap and the annular abutment shoulder of the container and said handle is rotated to twist said blade-like portion the skirt of the cap is engaged in one of said grooves and the cap is forced away from the container.

5. A cap lifter for removing a vacuum seal cap, having a downwardly extending skirt, from a container having an annular shoulder of given radial width spaced slightly below the skirt, comprising the combination of a curved rib having a concave longitudinal edge, the ends of the rib being rounded, a neck of biconvex longitudinal cross section fixedly supporting the rib and extending transversely from the side of the rib opposite the concave edge, the length of the neck being substantially less than the length of the rib, and a handle fixedly supporting the neck for inserting the concave edge of the rib between the skirt and the shoulder and against the container and for twisting the neck so as to force one end of the rib against the shoulder and the other end against an inside portion of the edge of the skirt.
